UNITED STATES PATENT OFFICE.

FRANCIS H. RICHARDS, OF HARTFORD, CONNECTICUT, ASSIGNOR, BY MESNE ASSIGNMENTS,
TO AMERICAN TYPOGRAPHIC CORPORATION, A CORPORATION OF NEW JERSEY.

MECHANISM FOR OPERATING ADJUSTABLE WORK-PERFORMING MEMBERS.

No. 902,326.

Specification of Letters Patent. Patented Oct. 27, 1908.

Application filed December 10, 1902. Serial No. 134,626.

To all whom it may concern:

Be it known that I, FRANCIS H. RICHARDS, a citizen of the United States, residing at Hartford, in the county of Hartford and State of Connecticut, have invented certain new and useful Improvements in Mechanism for Operating Adjustable Work-Performing Members, of which the following is a specification.

This invention relates to an organization of devices adapted for coöperative association with one or more members each of which may be capable of and upon adjustment is designed for performing work of some description.

In many classes of mechanisms and machines embodying members such as have just been referred to, it is material to the performance of the functions for which such mechanisms or machines are designed that each of the adjustable members (provided there are a plurality thereof) should be capable of being freely shifted and brought into a predetermined position in order that the member may properly coöperate with the object or surface upon which it is to act. It is moreover highly important, in a practical working machine, that such member when it shall have been adjusted and is in the act of performing its intended function, should be accurately precisionized in working position and rigidly held so that looseness or freedom of fit that may exist in order to permit it to be freely shifted during adjustment, shall be suppressed or taken up, the continued operation of the mechanism or machine necessitating, of course, that each adjusted member be ultimately returned to its normal or inoperative position.

The present invention is directed to the provision of parts and devices so related and organized as to enable these results to be accomplished with facility and in such a manner as to render the work performed by the adjusted member of a highly satisfactory nature.

In a mechanism embodying my present invention, means will therefore ordinarily exist for adjusting the adjustable members until the selected member shall have attained at least approximately the predetermined position requisite for it to perform the work for which it is designed, each such member being, moreover, so constructed and related to the guide surfaces by which its adjusting

movement is determined as to freely permit such motion to be imparted to it, combined with the adjustable members and coöperative with each when the same shall have thus been shifted and is about to perform its work, there is a device or means for giving it its final, precise position and for firmly and rigidly holding it in such precisionized position.

I have set forth in the drawings attached to the present specification an embodiment of the present mechanism, and in these drawings, Figure 1 is a vertical longitudinal section illustrating such embodiment, the plane of the section coinciding with the axis of the carrier upon which the plurality of adjustable work-performing members are mounted, and which plane in this instance extends transversely to the axis of the main operating shaft. Fig. 2 is a similar sectional view, the plane of this section, however, being at right angles to the plane yielding the section of Fig. 1 and that portion of the mechanism to the left of the plane of the section being viewed. Fig. 3 is a plan view, a portion of the inclosing casing being omitted for the purpose of clearly showing parts lying beneath. Fig. 4 is a section on a plane transversely disposed to the plane of Fig. 1. Figs. 5 and 6 are detail views illustrating the means comprised in the present mechanism for shifting each adjustable member toward its predetermined working position, Fig. 5 indicating the position of the parts immediately prior to the occurrence of the shifting movement, and Fig. 6 representing the relative position while the adjustable member is in its adjusted position.

Similar characters of reference designate corresponding parts in all figures.

The present invention is applicable to a wide variety of machines and mechanisms in which a member is capable of a shifting movement for the purpose of bringing it into a predetermined position by reason of its being so related to the guide faces which determine the character of such shifting movement as to enable it to be freely moved therealong and which member when so shifted to approximately its final position, is thereupon advantageously accurately precisionized as to position and rigidly held during such period as the member performs its work. Such conditions and requirements prevail in many classes of typographic machines, and I have

therefore chosen so much of a typographic machine as includes a carrier, a plurality of adjustable impressors mounted thereon and a mechanism for effecting the adjustment of the members and the working of each adjusted member in turn.

In the manufacture and assembling of the various parts to form a complete and practical operative machine, it is contemplated that such a degree of engineering and constructive skill shall be employed as to produce a proportion of parts and character of connections adequate to transmit the necessary forces and to create the necessary rigidity and precision. The exercise of such skill on the part of the designer and constructor to meet various conditions may therefore result in a mechanism the details of construction of which differ from those illustrated in the drawings hereto attached, which are accordingly to be taken in the sense of being illustrative only of these particular matters.

The various operative parts comprised in the mechanism will be mounted upon a suitable supporting fixture or fixtures of such shape and proportion as are determined, to a large extent, by the particular machine or mechanism in whose construction and organization an embodiment of the present invention enters. In the present illustrated embodiment, the support aforesaid is afforded by a frame or casing, designated in a general way by 1. In the present embodiment also, a plurality of adjustable members are indicated, such members being in the nature of typographic impressors, designated without discrimination by 2. These impressors are furthermore mounted upon slides such as 3, rendering the impressors adjustable. Any one of these slides and hence impressors may be brought in line with the predetermined point hereinafter referred to as the working point; to enable this to be effected, the slides may be mounted upon a shiftable carrier, and while such carrier may obviously be of various forms and susceptible of a variety of movements in order to shift a given slide from a position out of alinement with the working point to a position in alinement therewith, I have for simplicity of construction represented a carrier, designated by 4, the same being rotative about an axis, defined by the carrier-supporting shaft 5, one of whose reduced shoulder-forming ends 6 is mounted in a bearing supported by a cross-bar 7 of the casing 1; the other reduced shoulder-forming end 8 of the shaft, rotates in a bearing supported by an overhanging arm 9 affixed to the frame or casing.

I have chosen to illustrate my invention as embodied in a mechanism in which an intermittent movement is imparted to the slide carrier, this latter being advanced at each step through an angular distance such that

the slides are brought successively in line with the working point. When a slide shall have been so positioned and before the carrier is advanced through the next angular movement, mechanism becomes operative to shift the said positioned slide and carry the impressor thereon toward its predetermined or working position, whereupon the slide, and hence its impressor, is caused to be accurately precisionized in position and the slide to be fixedly held in engagement with its guide, thus rendering the adjustable member, that is the impressor on the shifted slide, rigid, while the impressor is subjected to the various forces and stresses incident to its working. I have deemed such a mechanism so constructed and so operative, sufficient to disclose the features of the invention, since obviously the invention is susceptible of application to a great variety of machines or mechanisms and in which the carrier is so shifted as to bring the adjustable members in line with the working point in other sequences than a consecutive one corresponding to the consecutive disposition of the members upon the carrier. And again, in point of time the consecutive periods consumed in replacing the adjustable member at the working point by others may be widely, as respects relative duration, different from those occupied in such substitution during the operation of the present simple mechanism. Proceeding, however, to a detailed description of the mechanism as it is illustrated in the drawings attached to the present specification, the intermittent motion of the carrier 4 is effected from a main shaft 10 assumed to be capable of continuous rotation from a suitable source of power (not shown) in driving connection with a pulley 11 on the main shaft. Interposed between the shaft 5 of the carrier and the main shaft 10, is an intermediate transmitting connection comprising a spiral gear 12, attached to the carrier shaft with which meshes a companion gear 13 mounted on a shaft 14 journaled in bearings in the sides of the frame, and having mounted on it a star wheel such as 15. Collars such as 16 may obviously be affixed to both the shafts 10 and 14 at the proper points to confine such shafts to their proper rotary movement. The actuator adapted to engage with the star wheel 15 is in this instance in the nature of an anti-friction roller 17, mounted upon an arm 18, extending from the main shaft 10 and which roller is so related to the star wheel as to impinge against the arms of such wheel one after another, the result obviously being, assuming that the shaft 10 is continuously rotating, an intermittent movement of the shaft 14 and hence of the carrier 4. There being in this instance, five slides upon the carrier, the star wheel 15 will also have five points or arms to effect, at the close of each step-by-step

movement of the carrier, the shifting of the slides thereon one after another into line with the working point.

Each slide 3 is movable in line with the axis of the carrier being situated in a corresponding guideway 19 therein. The cross-sectional form of each slide is such, with relation to its guideway, that the slide is readily and freely movable lengthwise of the guideway save at such times as the slide shall, by an extraneously applied pressure, be accurately positioned (precisionized) and forced into firmer engagement with the faces of the guideways. While the application of the present invention is not limited to any particular construction or relation of contacting faces of the slide and the guideway in which it is mounted, I may, in order to obtain the foregoing results, form each slide with a pair 20 of longitudinal laterally convergent faces such as 20, 20, adapted to bear against correspondingly inclined faces adjacent to the mouth of the guideway and a pair of substantially parallel faces such as 21, 21, adapted 25 to bear against corresponding faces adjacent to the base of the guideway. Suffice it here to say, in further description of the illustrated slide construction, that each slide is provided with a longitudinal projecting rib 30 such as 22, which enters a corresponding channel in the guideway and prevents the slide from dropping out laterally from the guideway.

The features of construction of adjustable working members, such as the present slides constitute, are not claimed herein, the same constituting the subject-matter of another application filed by me on July 10, 1902 Serial No. 115,010.

40 Immediately upon the arrival of a slide in line with the working point (which in this case is at the rear of the machine), means will engage with the slide to effect its longitudinal adjustment. The means for accomplishing such shifting movement is, in this case, in the nature of an arm 23 having a socket 24 at its free end adapted to engage with a pin or projection 25 extending laterally from the slide. The arm 23 is swung inward to engage the socket therein with the pin on the slide through the instrumentality of a cam 26 affixed to the driving shaft 10, and the cam is operative to actuate the arm through a link 27, upon which is mounted an anti-friction roller 28 against which the cam is adapted to bear. That end of the link 27 which is adjacent the driving shaft, is bifurcated and embraces the shaft whereby the end of the link is supported and guided, while the opposite end of the link is pivotally connected to an arm 29 functioning in a manner that will presently be adverted to in detail.

The longitudinal movement of the link is transmitted to the socketed arm 23 through means preferably so constructed as to per-

mit the final movement of the link to take place without operating to continue the swinging motion of the arm, which effects the engagement of the socket on the arm with the pin on the shifted slide. The means disclosed for accomplishing results, as aforesaid, comprises a shoulder 30 upon the link 27, which is adapted to bear against the contact face of an arm 31 extending from a shaft 32 journaled in a bearing 33 at the upper portion of the frame and a bearing 34 in a bracket 35 constituting a fixture of the framing. To this shaft 32 the aforesaid arm 23 is likewise affixed, and hence, when the link is shifted forward in the direction of the arrow 75 70 75 80 85 90 95 100 105 110 115 120 125 130 in Fig. 3, the shoulder 30 forces the arm 31 to the rear and causes the arm 23 to advance and engage its socket with the pin on the slide. A spring such as 36 may be utilized for insuring contact between the shoulder and the contact face of the arm 31, and hence assures the impart action of a definite amount of movement to the arm 23 at each rotation of the cam 26. Assuming now that the pin on the slide alined with the working point 90 has engaged with the socket in the arm 23, the slide is now ready to be shifted in its guideways to bring the impression device thereon to the working point. This is accomplished, in the organization disclosed, by lifting the arm 23, thus carrying the slide longitudinally of the guideway in which it is mounted. This lifting of the arm 23, and consequently of the arm 31 and the shaft 32 to which the two arms are attached, may be effected through a suitable cam device. In the present instance the reciprocation of the mentioned parts simultaneously with which occurs the shifting of the alined slide to bring the impresser thereon to the working point 105 110 115 120 125 130

The rocking motion of the rock shaft 39 is effective to reciprocate the shaft 32 and the parts connected to it through a rock lever 45 (here shown as a continuation of the rock arm 41). This rock lever 45 is bifurcated at its free end and embraces a block 46 130

loosely mounted upon the shaft 32, but immovable longitudinally with reference thereto by restraining collars 47 and 48 on the shaft. Each side portion 49 of the bifurcated portion of the lever is slotted, see the slot 50, and in each slot is located a pin or trunnion 51 extending from the block. Such being the construction, it is plain, assuming the cams 37 and 38 to be of the proper contour and properly related to each other, that a single rotation of the driving shaft is effective to cause an upward movement of the shaft 32 and subsequently the return thereof to its normal or lowermost position. The cams 37 and 38 are moreover of such configuration as to cause a dwell, representing a portion of the period consumed in each single rotation of the main driving shaft, when the shaft 32 is in both extreme positions of its reciprocatory movement as aforesaid. During one of these temporary periods of rest, to wit, the one corresponding to that position of the shaft 32 in which the same is at its lowermost position, the engagement of the socket on the arm 23 with the pin on the alined slide will be effected, and at the other temporary cessation of movement of the slide, the adjustable member, that is the impressor on the slide, will be positioned approximately at the working point preceding the performance of the work which it is contemplated that it shall do. Prior to the execution of such work, however, it is desirable in practice, in order that satisfactory results shall be attained, that an adjustable member or impressor should be more precisely located or precisionized in its definite working position than by the mere shifting of a slide which must necessarily be slidably fitted to its ways to permit it to be slid therealong and hence liable to change its position when pressure is brought to bear on the impressor thereon mounted; when working, it should moreover be as rigid in its working position as may be in order to eliminate the ill effects incident to any looseness which it might have by reason of the fact that the slide must be so constructed and related to its guideways as to permit it to be freely slid therealong.

In order to accurately precisionize and fixedly maintain the adjustable member in its working position, means are provided constituting one feature of the present invention, for firmly pressing the slides upon which the impressors are carried against the respective guideways in which they are mounted. This pressure is exerted, in the particular construction set forth, against the arm 23 when the same shall have been elevated to shift the impressor into the working point, and I utilize for exerting the such pressure, a presser such as 52, in this case in the nature of a presser arm, secured to a shaft 53 journaled in a bearing 54 in the aforesaid bracket

35 and a bearing 55 supported by the frame B. Collars such as 56, 56 secured to the shaft serve to prevent its longitudinal movement, while the angular movement thereof to force the arm 52 firmly against the arm 23 70 results from a longitudinal movement of the link 27 occurring subsequent to that movement thereof which engages the socketed arm 23 with the pin on the alined slide. It will be noticed that the cam 26 has a portion 75 57 of slightly larger radius than the portions of the working face of the cam immediately adjacent. It is this portion of larger radius that continues the longitudinal movement of the link to slightly turn the shaft 53 in its 80 bearings. This angular movement of the shaft 53 takes place after the shaft 32 has been raised to bring the impressor more or less approximately into the working point; the parts are preferably so proportioned that 85 when the final forward movement of the link takes place, the contact face of the arm 31 will have been raised out of the path of the shoulder 30 on the link and hence the pressure precisionizing the slide and forcing the 90 same firmly against the faces of its guideway will be exerted by the presser arm 52 directly against that portion of the arm 23 which is immediately adjacent to the location of the socket therein. It should here be stated 95 that the width of the arm 23 where pressed against by the presser arm 52, is sufficient to preclude the disengagement of the two at any time and that the correct and certain action of the link 27 is here assured by a spring such 100 as 58 which serves to force the cam roll 28 on the link toward its operating cam 26.

So far as the construction, organization and operation of a locating and precisionizing mechanism, such as has been hereinbefore 105 described, is concerned, it is obviously not restricted in its use or application to any particular mode or character of working which the adjustable members perform. I have, by way of illustration, however, (such representation not being therefore in any sense a limitation) indicated a platen for coöoperating 110 in succession with the successively located and precisionized impressors. In the conventional representation thereof set forth, the 115 platen is designated by 70, the same being in the form of a roller mounted at the end of a rock arm 59 secured to a rock shaft 60 mounted in bearings 61, and operated by a cam 62 adapted to impinge against a cam roll 120 63 mounted on a link 64 pivoted to an arm 65 extending from the aforesaid rock shaft 60. A spring 66 insures the proper coöperation of the cam 62 with the cam roll 63 and the operation of the cam is so timed with relation 125 to the operation of the other cams already described that the platen is caused to coöperate with each impressor when the same shall have arrived at the working point and the slide upon which the impressor is mount- 130

ed is pressed against the faces of its guideway. Means are also provided in the illustrated mechanism for holding the several slides in correct normal position in order that 5 the socket upon the arm 25 may engage with the pin on a slide, when the slide shall have been brought into alignment with the working point. The means herein shown for this purpose performs the further function of 10 locking all the slides from lengthwise movement in their guideways with the exception of the slide whose pin 25 may be at any given time opposite the socket in the arm 23. This means is in the nature of a locking 15 groove, such as 67, the plane of which is normal to the axis of the slide carrier and the groove being in such position that the pins or projections 68 on the respective slides are free to travel through the groove when the 20 slides are in their normal position. This groove 67 is in this instance formed in an annular fixture 69, here shown as detachably secured to the frame 1, the fixture being cut away at such a point as to enable the lifted 25 arm 23 to shift the aligned slide lengthwise of its guideway and locate the adjustable impressor at or near the working point. The configuration of the cams and their relative timing are so related as to cause the return of 30 the parts after actuation, in proper order, to their normal positions, following which a recurrence of the operations as hereinbefore described takes place.

Conciseley the operation of a mechanism 35 such as has been described takes place as follows: Assuming the driving shaft 10 to be in rotation and that an intermittent movement is imparted through the star wheel 15 and engaging spiral gears 12 and 13 to the carrier 40 4, each slide being brought in turn in alignment with the working point, the first operation occurring when a slide shall have arrived thereat is the movement of the arm 23 inward to cause the socket thereon to engage 45 with the pin 25 on the slide, this resulting from the longitudinal movement of the link 27 imparted to it from the cam 26 which forces the shoulder 30 against the contact face of the arm 31. Further movement of 50 the driving shaft brings into action that cam of the pair 37, 38 which serves to raise the shaft 32 and hence the arm 23 and thereby locate the impression device 2 at the working point. Immediately following the arrival of 55 this device at such point the forward motion of the link 27 is continued by reason of the portion 57 of the cam 26 coming into contact with the anti-friction roller 28 on the link. This results, as will be understood from the 60 preceding description, in the forcible pressure of the presser arm 52 against the arm 23, thus precisionizing the slide and impressor and rigidly holding them in the predetermined position corresponding to the working position of the impressor. The working of the

adjustable device or member (impressor) now takes place, that is to say, in this case the platen 70 is rocked against the same by the operation of the cam 62 against the cam roll 63. The parts now return to their former 70 position, the presser bar 52 first releasing the arm 23 through the action of the spring 58 upon the disengagement of the part 57 of the cam 26 from the cam roll 20; after this the shaft 32 is caused to descend, the slide to be 75 drawn downward and the shoulder 30 on the link 27 is reengaged with the contact end of the arm 31. The parts are now ready for passing through another cycle of movements as before. 80

Having thus described my invention, I claim—

1. The combination with a rotary die-carrier, of a series of dies movable upon the carrier; means for rotating the carrier and stopping the same with one of the dies adjacent to the working position; an arm for engaging the die; means for actuating the arm; means for raising the arm thereby to shift the die; and means for reinforcing the arm and pressing it more strongly into engagement with the die. 85

2. The combination with a rotary die-carrier; means for rotating the carrier; a series of die-slides individually shiftable upon the carrier; means for maintaining the dies normally in their idle position; a lug upon each slide; an arm mounted upon a reciprocatory rock-shaft and provided with an opening constructed to receive the lug of the slide; a 95 sleeve surrounding the rock-shaft and connected therewith; means for oscillating the sleeve to rock the arm; and means for reciprocating the arm through the sleeve. 100

3. The combination with a rotary die-carrier; means for rotating the carrier; a series of die-slides individually shiftable upon the carrier; means for maintaining the dies normally in their idle position; a lug upon each slide; an arm mounted upon a reciprocatory 105 rock-shaft and provided with an opening constructed to receive the lug of the slide; a sleeve surrounding the rock-shaft and connected therewith; means for oscillating the sleeve to rock the arm; means for reciprocating the arm through the sleeve; a reinforcing arm adjacent to the position occupied by the lug receiving arm at the limit of its excursion; and means actuated by the sleeve oscillating means for moving the reinforcing 110 arm against the former arm. 115

4. The combination with a die-carrier; a series of dies mounted upon the die-carrier; a die upon each slide; a continuously-operating cam-shaft; a cam thereon for intermittently rotating the carrier; an arm organized to engage the die-slide which is stopped adjacent thereto; means connected with the cam-shaft for pressing the arm 125 against the slide; means actuated by a cam 130

on the shaft for raising the arm; means actuated by the same cam-shaft for imparting locking pressure to the arm; and means actuated by the cam for lowering the arm.

5. The combination with a die mounted upon a slide; of an arm for engaging the slide; means for positively moving the arm into engagement with the slide; means for positively raising the arm; and means for 10 positively lowering the arm.

6. The combination with a die mounted upon a slide; of an arm for engaging the slide; means for positively moving the arm into engagement with the slide; means for 15 positively moving the arm to shift the slide; and means for positively returning the arm to shift the slide to its original position.

7. The combination with a die mounted upon a slide; a projection thereon; an arm 20 provided with a mating cavity and mounted upon a reciprocatory rock-shaft; a sleeve surrounding the rock-shaft and splined thereto; means for positively oscillating the sleeve to cause the arm and projection to mate; means for 25 positively giving an excursion to the rock shaft to shift the slide; means for positively returning the rock-shaft; and means for returning the sleeve to release the arm from the slide.

30 8. The combination with a shiftable member, of a member constructed to engage the same and mounted upon a shaft; a sleeve surrounding the shaft, held from reciprocation and splined to the shaft; means for rocking the sleeve in one direction positively; means for returning the same to its normal position; a rock-shaft transverse to said shaft; an arm 35 fast thereon and engaging the end of said former shaft; a cam shaft; cams thereon; a pair of arms fast on said shaft and riding upon opposite sides of said cam-wheel whereby the shaft is positively shifted in both excursions of its reciprocation.

9. The combination with a series of die- 45 slides; a die upon each slide; a rotary carrier for the slides; means for rotating the carrier upon a plane transverse to the plane of individual movement of the slides and comprising a continuously-rotating driving shaft; an engaging member upon the driving shaft; a 50 star wheel adapted to be engaged by the member; and a worm gear having one member fast with the carrier and one fast with the star wheel whereby continuous intermittent 55 motion is imparted to the carrier.

10. The combination with a series of dies, of a series of slides therefor; a carrier for the dies mounted for rotary movement in a plane transverse to the plane on which the slides 60 are shiftable; an engaging face upon each slide; an arm constructed to engage the same; means for bringing the arm into engagement therewith; and means for moving the arm to shift the slide.

65 11. The combination with a head, of

means for rotating the head step by step; die-slides mounted upon the head and shiftable transversely to the plane of rotation of the head; a channel adjacent to and surrounding the head and having in one of its walls a transverse channel; a lug upon each die-slide and constructed to traverse the channel; and means for imparting transverse movement to each slide when it comes adjacent to the transverse channel, the organization being 75 such that upon the shifting of the slide its die will be brought into working position and the head locked from rotation by the lug within the transverse channel.

12. The combination of a plurality of dies 80 each mounted upon a slide; a projection on each slide; a reciprocatory rock-shaft; an arm provided with a mating cavity and mounted thereon; a sleeve surrounding the rock shaft and splined thereto; means for 85 positively oscillating the sleeve to cause the arm and projection to mate; means for positively giving an excursion to the rock shaft to shift the slide; means for positively returning the rock shaft to return the slide; and 90 means for returning the sleeve to release the arm from the slide.

13. The combination with a plurality of shiftable members, of a member constructed to engage the same individually and mounted 95 upon a shaft; a sleeve surrounding and splined to the shaft, and held from reciprocation; means for oscillating the sleeve in one direction positively; means for returning the same to its normal position; a rock shaft 100 transverse to said shaft; an arm fast thereon and engaging the end of said former shaft; a cam shaft and cam faces; a pair of arms fast on said shaft, and engaging opposite sides of said cam faces whereby the member engaged 105 is positively shifted in both directions.

14. The combination of a plurality of dies each mounted upon a slide; a rotary carrier provided with ways for the slides; a projection on each slide; a reciprocatory rock shaft; an arm provided with a mating cavity and mounted on the rock shaft; a sleeve surrounding the rock shaft and splined thereto; means for 110 positively oscillating the sleeve to cause the arm and projection to mate; means for positively giving an excursion longitudinally to the rock shaft to shift the slide; means for 115 positively returning the rock shaft longitudinally to return the slide; and means for returning the sleeve to oscillate the rock shaft 120 and release the arm from the slide.

15. The combination with a plurality of shiftable members, of a rotary carrier therefor; means to rotate the carrier step by step; a member constructed to engage the shiftable members individually and mounted upon a reciprocatory rock shaft; a sleeve surrounding the shaft capable of rocking the same, and held from reciprocation therewith; means for oscillating the sleeve in one direc- 130

tion positively; means for returning the same to its normal position; a rock shaft transverse to said reciprocatory rock shaft; an arm fast thereon and in engagement with the end of the reciprocatory rock shaft; a cam shaft and cam faces; a pair of arms fast on said shaft and engaging cam faces on opposite sides of said cam shaft whereby the member engaged is positively shifted in both directions.

16. The combination of a plurality of dies each mounted upon a slide; a rotary head provided with ways for the slides; a lug on each slide; a channel surrounding the head and constituting a raceway for the lugs and effective to hold the slides in an idle position; a transverse channel communicating therewith adjacent to the working position of the dies; a projection on each slide; a reciprocatory rock shaft; an arm provided with a mating cavity and mounted on the rock shaft; a sleeve surrounding the rock shaft and splined thereto; means for positively oscillating the sleeve to cause the arm and projection to mate; means for positively giving an excursion longitudinally to the rock shaft to shift the slide, bring the die into working position and cause the lug to enter the transverse channel and lock the head while the die is at working position; means for positively reinforcing and locking the arm; means for positively returning the rock shaft longitudinally to return the slide; and means for returning the sleeve to oscillate the rock shaft and release the arm from the slide.

17. The combination of a plurality of dies each mounted upon a slide; a rotary head provided with ways for the slides; means for advancing the head step by step; a lug on each slide; a channel surrounding the head and constituting a raceway for the lugs and effective to hold the slides in an idle position; a transverse channel communicating therewith adjacent to the working position of the dies; a projection on each slide; a reciprocatory rock shaft; an arm provided with a mating cavity and mounted on the rock shaft; a sleeve surrounding the rock shaft and splined thereto; means for positively oscillating the sleeve to cause the arm and projection to mate; means for positively giving an excursion longitudinally to the rock shaft to shift the slide, bring the die into working position and cause the lug to enter the transverse channel and lock the head while the die is at working position; means for positively reinforcing and locking the arm; means for positively returning the rock shaft longitudinally to return the slide; and means for returning the sleeve to oscillate the rock shaft and release the arm from the slide.

18. The combination with a plurality of shiftable members, of a rotary carrier therefor; a continuously rotating driving shaft; means driven thereby to rotate the carrier

step by step; a reciprocatory rock shaft; a member constructed to engage the shiftable members individually and mounted upon the rock shaft; a sleeve surrounding the shaft, capable of rocking the same, and held from reciprocation therewith; means actuated by the driving shaft for oscillating the sleeve in one direction positively; means for returning the same to its normal position; a rock shaft transverse to said reciprocatory rock shaft; an arm fast thereon and in engagement with the ends of the reciprocatory rock shaft; cam faces on the driving shaft; a pair of arms fast on said rock shaft and engaging cam faces on opposite sides of said driving shaft whereby the member engaged is positively shifted in both directions and positively locked in its shifted position.

19. The combination with a rotary carrier head, of ways thereon parallel with the axis of rotation; a plurality of shiftable slides; a die mounted upon each slide; a continuously rotating driving cam shaft; a star wheel having an arm for each slide; a striker on the driving shaft for rotating the star wheel intermittently; a worm gear driven thereby to rotate the carriage step by step; a lug on each slide; a channel surrounding the head and constituting a raceway for the lugs effective to hold the slides in an idle position; a transverse channel communicating therewith adjacent to the working positions of the dies and at the position occupied by the lugs at the intermissions of movement of the head; a projection on each slide; a reciprocatory rock shaft; an arm provided with a cavity constructed to mate with the projections of the slide and mounted on the rock shaft; a sleeve surrounding the rock shaft capable of rocking the same and held from reciprocation therewith; a link supported by the driving shaft; a cam actuated by the driving shaft for advancing the link and positively oscillating the sleeve in one direction; a rock shaft transverse to said reciprocatory rock shaft; a sleeve on the end of the reciprocatory rock shaft; lugs projecting therefrom; an arm fast on the transverse rock shaft and provided with a forked, bifurcated end in engagement with said lugs; cam faces on the driving shaft; a pair of arms fast on said rock shaft and engaging cam faces on opposite sides of said driving shaft, one arm for positively giving an excursion longitudinally to the rock shaft to shift the slide, bring the die into working position and cause the lug thereon to enter the transverse channel and lock the head while the die is at working position, and one of said arms for positively returning the rock shaft longitudinally to return the slide whereby the slide engaged is positively shifted in both directions and positively locked in its shifted working position; an arm adjacent to the position occupied by the shifting arm when the die is at working position for posi-

tively reinforcing and locking such arm; an arm fast upon the reinforcing arm and pivoted to the link whereby further advance thereof will press the slide firmly against its way; means for returning such reinforcing arm; means for returning the sleeve to oscillate the rock shaft and release the arm from the slide; a roller impressor adjacent to the working position; a rock shaft; an arm carried thereby and carrying the impressor; a link for rocking the impressor shaft and supported by the driving shaft; and a cam thereon for advancing said link.

20. The combination with an adjustable work-performing member, of means for locating the said member approximately at its working position, means for presenting the work to said member and means for precisionizing the said member into its working position and for rigidly maintaining it at such position during its working.

21. The combination with an adjustable work-performing member, of a reciprocatable slide on which the same is mounted, means for locating the slide with the work-performing member approximately at its working position, and means for precisionizing the position of the slide to precisionize the position of the work-performing member and for rigidly holding the slide at such position during the working of the said member.

22. The combination with a carrier, of a slide mounted to be freely shiftable thereon, a locator arm for shifting the slide to its approximate predetermined position, and a precisionizing arm separate from said locator arm for then placing the slide in its final position.

23. The combination with a carrier provided with a guide way having convergent longitudinal faces adjacent to its mouth, a slide fitted to said guide way to be freely shiftable thereon, an oscillating and reciprocatory locator arm for shifting the slide to its approximate predetermined position, and an oscillating and reciprocatory precisionizing arm for giving said slide its final position.

24. The combination with a rotatable carrier, of means to angularly adjust said carrier, a plurality of slides mounted to be independently freely shiftable thereon, a locator for shifting a selected slide to its approximate predetermined position, and a precisionizing device for shifting it to its final predetermined position.

25. The combination with a carrier, of a slide mounted to be freely shiftable thereon, a work-performing member adjustable on said slide, a locator arm adapted to engage with the slide, means to shift the arm to shift the slide and the work-performing member to its approximate working position, a precisionizer for then accurately positioning the slide and member, and a single member for

actuating both the locator and the precisionizer in proper sequence, and for locking both during the working period.

26. The combination with a carrier, of a slide mounted to be freely shiftable thereon, an adjustable work-performing member on the slide, a locator adapted to engage with the slide and shift the work-performing means to its approximate working position, a precisionizer for then accurately positioning the slide, and a single member for actuating both the locator and the precisionizer in proper sequence.

27. The combination with a carrier, of a slide mounted to be freely shiftable thereon, an adjustable work-performing member on the slide, a locator adapted to engage with the slide and shift the work-performing means to its approximate working position, a precisionizer for then accurately positioning the slide, a single member for actuating both the locator and the precisionizer in proper sequence, and cams for actuating said single member.

28. The combination with an adjustable carrier, of a plurality of slides mounted to be freely shiftable thereon, adjustable work-performing members on the slides, combined locating and locking means adapted to engage with a slide when aligned with the working point and shift a work-performing member thereon to its approximate working position, a precisionizer for then accurately positioning and firmly holding the slide, a locking device for assuring the correct normal position of the slides, and cams for actuating the locating means and precisionizer in proper sequence.

29. The combination with a rotary head having ways, slides mounted in the ways, a die carried by each slide, means for rotating the head, means for shifting the individual slides upon said ways transversely to the plane of rotation, and means for engaging a shifted slide for preventing rotation of the head while the slide is away from the idle position.

30. The combination with a head, of means for rotating the head intermittently, slides mounted upon the head for movement parallel with the axis of rotation of the said head, work-performing members carried by each of the slides, means for normally holding the slides to maintain their work-performing members in idle position, means for shifting each slide relatively to the head individually upon its arrival at a certain point for bringing a particular member thereon into a working position, and means operable in conjunction with the shifted slide for locking the head against rotation while such slide is out of idle position.

31. The combination with a rotary head.

provided with ways disposed parallel with the axis of rotation, slides mounted in the ways, a die carried by each slide, and means for shifting the slides upon the ways for bringing the dies thereon into working position, and for locking the head against rotation.

Signed at Nos. 9-15 Murray street, New York, N. Y., this 9th day of December, 1902.

FRANCIS H. RICHARDS.
